WILLIAM A. BOND, OF LYNNFIELD, MASSACHUSETTS, ASSIGNOR TO UNITED SHOE MACHINERY COMPANY, OF PATERSON, NEW JERSEY, A CORPORATION OF NEW JERSEY.

SHOE-SUPPORT.

1,161,832.

Specification of Letters Patent.

Patented Nov. 30, 1915.

Application filed October 5, 1910. Serial No. 585,417.

To all whom it may concern:

Be it known that I, WILLIAM A. BOND, a citizen of the United States, residing at Lynnfield, in the county of Essex and State of Massachusetts, have invented certain Improvements in Shoe-Supports, of which the following description, in connection with the accompanying drawings, is a specification, like reference characters on the drawings 10 indicating like parts in the several figures.

This invention relates to work supports and particularly to supports for holding shoes for the operation of shoe machines which perform successive operations around 15 the heel portion of a shoe.

The embodiment of the invention herein shown is particularly suitable for supporting shoes for the operation of the machine which forms the subject matter of United 20 States Letters Patent No. 1,085,595, granted February 3, 1914, to Charles De Minico.

The object of this invention is to provide a shoe support which will facilitate the presentation and manipulation of a shoe while 25 it is being operated upon by a machine which inserts tacks or other fastenings in the heel seat or by a machine for performing other operations upon the heel or rear portion of a shoe.

30 An important feature of the invention comprises a last engaging device and a sustainer therefor, which have relatively sliding contacting surfaces that are curved about a center located a substantial distance above the bottom of the last on the engaging device to direct movement of the device in an arc. The construction enables the last engaging device, which may be a last spindle, to be positioned either vertically or at various 35 inclinations to the vertical so that the heel seat portion of the last may be readily brought to a level position for the reception of heel seat lasting tacks or for other shoe-making operations. In the construction 40 shown the spindle has a spherically convex base and the spindle support a spherically concave face which engages the convex base of the support, and the curvatures of the engaging faces are struck from points substantially 45 above the end of the spindle and preferably from the same point.

A further feature of the invention consists in means for limiting movement of the spindle base so that the movement of the last 50 carried by the spindle will be limited to a

distance less than the width of the heel seat of the last.

Other features and objects of the invention will be apparent from a consideration of the following description and claims in 60 connection with the accompanying drawing, in which—

Figure 1 is a side elevation of the improved jack and a portion of the machine to which it is applied; Fig. 2 is a sectional view of the spindle for supporting the last and the head for supporting the spindle in adjustable relation to the operative parts of the shoe machine; Figs. 3 and 4 are sectional details taken respectively on lines 3—3 and 70 4—4 of Fig. 1.

The jack proper is supported by a lever 2 pivoted to the main frame A of the machine by a bolt 4. The lever 2 is given movement by a rod 6 in connection with a cam 8 on 75 the main shaft of the machine in timed relation to the action of a pounding up element 10 of the machine and a side pounder or blocking element which reciprocates within a part 12. The cam 8 which carries 80 two projections of different length, as shown in Fig. 3, acts upon a roller 9 carried by a pin 10 on a slide 13 having a slot 15 through which passes the main shaft of the machine. To the upper end of the slide 13 is clamped 85 by a bolt 17 a rod 14 on the upper end of which is a thumb nut 16. Between the thumb nut 16 and a yoke 18, to which the rod 6 is attached, is a spring 20. As the projections of the cam 8 act downwardly 90 upon the pin 10 on the slide 13, which is connected with the rod 14, it imparts movement to the yoke 18 through the spring 20 and thence by the rod 6 jointed at 21 to the right-hand end of the lever 2 which turns 95 about the bolt 4 as a fulcrum and raises the left end of the lever and the jack supported thereon. Upon release of downward pressure by the cam 8 a retractile spring 22, called the jack spring, raises the right end 100 of the lever 2 and restores the jack to its lower or normal position. The interposition of the spring 20 gives the jack a resilient support and by taking up the excess movement of cam 8 prevents the application 105 of more upward pressure against the operative parts of the machine than is necessary for the proper performance of their various functions. The projections on the cam 8 are unequal for a purpose to be sub-

110

sequently explained. The end 24 of the lever 2 is bifurcated and each bifurcation is provided with a slot 26 through which passes a bolt 28. By this bolt a member 29 is clamped to the bifurcation of the lever 2 and by means of the slots therein it may be adjusted toward and away from the machine. When clamped in adjusted position in the slots 26 the bolt serves as one axis of a universal joint which supports a foot block 30. The other axis of the universal joint is provided by screws 31 passing through lugs on the foot block 30 and engaging the member 29. The universal joint permits free movement of the entire jack in so far as permitted by the stop ring 44, to be presently described.

Pivoted to the foot block 30 by a bolt 34 is a member 36 having a screw-threaded hole 20 at the upper end and provided at the lower end with a flattened extension having therein a slot 38. By means of this slot and a bolt 40 the angular position of the member 36 may be adjusted and rigidly secured 25 relatively to the foot block 30.

To prevent the jack from swinging out too far a stop is provided which consists of a bracket 42 attached to the frame of the machine and a stop ring 44 which embraces 30 the member 36 of the bracket and is pivoted to the base 42. The ring 44 is frictionally held in adjusted position by a screw 41 which clamps together the split sections of the bracket 42 upon the ring. When the 35 jack is swung outwardly from its operative position, shown in dotted lines in Fig. 1, it is caught by the stop ring 44 and held in the position shown in full lines in the same figure. The distance the jack moves outwardly may be varied by adjusting the ring 40 at an inclination to the horizontal and tightening the screw 41.

The upper end of the member or support 36 is slotted and screw threaded, and into 45 it a threaded rod 46 is screwed. This rod may be rigidly clamped in adjusted position by means of a split ring 48 and a screw 50. Attached to the rod 46 by a pin 52 is a head 54 which is shaped like an inverted 50 dome and has a heavy rounded peripheral portion or rim adapted to be grasped by the hand. Inset into the top of the member 54 and secured thereto by machine screws 56 is a plate 58 of uniform thickness having 55 a slight concavity downward and provided with an opening 60. The under surface of the mushroom shaped base 62 of the spindle support 64 has a curvature corresponding to that of the upper surface of the plate 58 with which it engages. These surfaces are held in frictional contact by a screw 63 inserted through the hollow spindle support 64 and, passing through a hole of the size of the screw in the base 62 of the support 60, through the opening 60 of the plate 58

and into screw threaded engagement with a retaining plate 66. This plate is larger than the opening 60 so that once the screw 63 is properly adjusted the spindle base 64 will be held frictionally against the top plate 58 of the dome but will be capable of movement within the area prescribed by the opening 60.

The last pin 68 which is screwed into the top of the support 64 is adapted to engage 75 a hole in a last. The curvature of the surfaces of the plate 58 and of the lower surface of the mushroom head 62 on the spindle support 64 is struck from a point so far above the top of the last pin and the size 80 of the opening 60 is such, that as the support 64 is made to pass through the circle prescribed by the screw 63 and the opening 60 a point on the periphery of the heel portion of the last will describe a circle of 85 substantially the size of that along which the lasting tacks are driven. This point is indicated at x in Fig. 1 of the drawing, the radius of curvature being the line $x-y$.

The jack cam 8 has two cam projections 90 upon it, one of which is longer than the other and the cam is timed to cause the shorter projection to lift the jack and shoe during the advance of the wiper over the upper so as to produce on the upper an overbending and then an inward rubbing and downward crushing action. This cam will hold the shoe up only while the tack is being driven and will then relieve the pressure and permit the jack spring 22 to lower 100 the shoe and avoid drag of the wiper over the upper during its retreat. The cam of the bottom beater or pounding-up member is timed to strike two blows during each cycle of the machine. The first blow is 105 struck after the wiper has retreated to uncover the stock and while the shoe is released from hard upward pressure and the second blow is struck after the longer projection on the jack cam 8 has raised the shoe 110 to meet the blow. Upon the second rise of the jack, the wiper being out of the way, the shoe is pressed up against the thin edge of the bottom rest 23 which sinks into the innersole and allows the shoe to rise higher 115 in response to the longer projection of the jack cam, so that in effect the second blow of the bottom beater on the shoe is harder than the first blow.

From the accompanying drawing and the 120 foregoing description the advantages and utility of the device will be apparent. The movement of the jack upon the pivots 28 and 31 enables the operator to readily place the last with its accompanying shoe parts 125 upon the spindle while in its outward position, and to move it toward the machine in proper relation to the operative parts thereof.

The adjustment provided by the pivot bolt 130

34, the slot 38 and clamp bolt 40 enable the operator to adjust and secure the support 36 at any angle with respect to the machine within the range of the slot 38. The screw 5 rod 46 and split ring 48 provide adjustment as to height to accommodate the jack to various sized lasts and different machines. The adjustment of the last pin 68 by means 10 of the convex surface of the mushroom base of the spindle 64 and the corresponding surface of the plate 58 is particularly important. The frictional engagement of these surfaces furnishes, when pressure is applied either by blows of the machine downward 15 or by movement of the jack upward, a positive connection between the spindle and the jack. When, however, no pressure is being applied to these surfaces they freely slide over each other and permit the operator 20 to easily, quickly and accurately adjust the work so as to level the last and present all portions of the work acted upon at the same height relative to the operating devices. Moreover if the jack is moved about 25 the outer limits of its path of movement, that is, by keeping the screw 63 against the walls of the opening 60, the result is that the nails and blows about the periphery of the shoe heel will always be delivered at the 30 same angle relatively to the bottom of the shoe or, what is the same thing, to the nail plate of the last.

In using my invention with a nailing or slugging machine the support 36 may be 35 held rigidly, the only movement of the jack under the nailing nozzle being due to the sliding upon each other of the curved surfaces of the parts 58 and 62. In this case if the jack is kept to the outer limit of its 40 path the jack spindle and last thereupon will describe a circle of substantially the diameter of that in which the nails or slugs are to be set in the heel. Hence, by this device little skill is required to set the nails or 45 slugs about the heel at evenly spaced distances from the periphery thereof.

The operation of the machine will now be 50 obvious without further explanation. It is to be understood, of course, that various modifications of the mechanism employed 55 may be made without departing from the spirit of the invention. Hence the scope of the following claims, in which effort has been made to define the invention, should 60 be interpreted with reference to, and as restricted only by, the state of the prior art.

Having described my invention, what I claim as new and desire to secure by Letters Patent of the United States is:—

60 1. A jack comprising a spindle for receiving a last, a spherically convex base for said spindle, and a spherically concave support for said spindle base the curvature of which is struck from a point materially above the 65 end of the spindle.

2. In a jack, means for supporting a last comprising a last engaging device and a sustainer therefor, relatively sliding contacting surfaces on said sustainer, and devices which are curved about a center located 70 a substantial distance above the bottom of a last on the engaging device to direct movement of the device in an arc.

3. In a jack, a spindle for engaging the pin hole in the heel portion of a last, said 75 spindle having a base provided with a spherically convex lower face, and a support for said base having a concave top face of similar curvature, one of said faces having a central circular aperture and the other 80 a co-operating projection adapted to engage the wall of said circular aperture to limit sliding movement of said base on the support, the diameter of said aperture and the curvature of said faces being proportioned 85 to the height of the spindle to cause said limiting means to restrict movement of the last carried by the spindle to a distance less than the width of the heel seat of the last.

4. In a last jack, means for supporting a 90 last with its tread face upward, said supporting means comprising relatively movable parts operatively connected together and constructed respectively with downwardly dished and downwardly convex sliding surfaces, combined with limiting means for said parts so arranged that a point on the periphery of the heel plate of the last will trace a substantially horizontal path 95 the shape and size of the curved portion of 100 the heel plate.

5. In a last jack, a spindle, a base on said spindle having a spherical surface the center of which is materially above the last, and a support for said spindle base having 105 a curved surface similar to and engaging that of said base.

6. A jack comprising a support, a rod engaging said support and constructed and arranged for longitudinal adjustment relatively thereto, a cap on said rod having a concave upper surface, a rim on said cap adapted for hand manipulation to adjust said rod, a spindle, and a spindle base having 110 a convex lower surface engaging said concave surface.

7. A jack comprising a support, a mushroom-shaped spindle base with its convex surface of a curvature the radius of which is greater than the height of the spindle 120 engaging the said support, and means restricting the movement of the convex surface over the support.

8. In a last jack, a spindle for the last, and a concave support for the spindle having a spherical curvature of a radius greater than the height of the spindle, the base of the spindle being adapted to be moved over the curved support whereby the heel seat 125 of the last may be leveled in all directions. 130

- 4
9. In a last jack, a last spindle having a convex lower surface, and a support for the spindle having a spherically concave upper surface which is struck from a point above the spindle and engages said convex surface so that adjustment of the surfaces over each other will level the last bottom. 60
10. A lasting jack comprising a hollow, slotted, internally threaded support, a threaded rod screwed therein, means for compressing the slotted portion of the support to grip the rod, a cap on said rod having its upper surface concave, a spindle base having a convex surface adapted to engage said concave surface, means limiting the movement of said surfaces upon each other, and a spindle on said base. 65
11. A lasting jack comprising a pivotally supported foot block, a support pivoted to said foot block for adjustment thereon, a rod adjustably held in said support, a head having a concave upper surface on said rod, and a spindle provided with an enlarged convex base engaging frictionally said concave surface. 70
12. A lasting jack comprising a hollow, inverted dome-shaped head having a thickened periphery, a plate seated in said thickened periphery and provided with a central opening and having its surfaces spherically curved from a center materially above the position of the last heel, and disposed with its concavity upward, a spindle having a mushroom-shaped spindle base with its convexity corresponding to and engaging said concave plate, a retaining plate beneath said plate, and means connecting said mushroom head and said retaining plate. 75
13. In a lasting jack, a foot block, a support provided with a hole in its upper end and pivotally adjustable on said foot block, a rod adjustably held in the hole of said support, a hollowed head on said rod provided with a thickened periphery, a concave plate seated in said thickened periphery and provided with an opening, a spindle base having a convexity corresponding to and engaging said concave plate and struck from a point above the spindle, a retaining plate beneath said concave plate, means passing through the opening in said concave plate connecting said base to said retaining plate, and a spindle on said spindle base. 80
14. In a jack, a foot block, a support pivoted to said foot block and provided with a slot in the lower end thereof, a clamping bolt passing through said slot and said foot block, a rod longitudinally adjustable in said support, a hollow head on said rod having a thickened periphery, a concave plate seated in the thickened periphery of said hollow head and provided with an opening, a spindle base having a convex lower face corresponding in curvature to that of said plate, a retaining plate beneath said concave plate, a bolt passing through the center of said spindle base and said opening in said concave plate and engaging said retaining plate, and a spindle supported by said spindle base. 85
15. In a jack, a spindle, a base on said spindle having a downwardly convex surface of a curvature struck from a point above the spindle, a support for said base having a curvature corresponding to and engaging that of said base, and means limiting movement of a point on the curvature of the base within the area of a circle larger than the heel plate, said limiting means and said curvatures restraining a point on the heel plate to movement within an area substantially equal to that inclosed by the heel seat lasting tacks. 90
16. In a lasting jack, a stop, comprising a rigidly supported base and a jack, an embracing ring extending through said base, and means for frictionally holding the ring therein in adjusted position. 95
17. In a jack, a spindle, a spindle support arranged for universal movement, and means restricting said movement, combined with automatically operating mechanism for raising the support twice in each cycle of the machine and alternately to different heights. 100
18. In a jack, a spindle, a spindle support arranged for universal movement, and means restricting said movement, combined with automatically operating mechanism for raising the support twice in each cycle of the machine and alternately to predetermined heights. 105
19. In a jack, a spindle, an abutment against which upward movement of the jack will press the shoe, and automatic power means for yieldingly forcing the jack and shoe upwardly against the abutment with pressures which vary automatically and to a predetermined extent in successive movements of the jack. 110

In testimony whereof I have signed my name to this specification in the presence of two subscribing witnesses.

Corrections in Letters Patent No. 1,161,832.

It is hereby certified that in Letters Patent No. 1,161,832, granted November 30, 1915, upon the application of William A. Bond, of Lynnfield, Massachusetts, for an improvement in "Shoe-Supports," errors appear in the printed specification requiring correction as follows: Page 2, line 30, for the word "bracket" read *jack*; same page, line 31, for the word "base" read *bracket*; and that the said Letters Patent should be read with these corrections therein that the same may conform to the record of the case in the Patent Office.

Signed and sealed this 18th day of April, A. D., 1916.

[SEAL.]
